UNITED STATES PATENT OFFICE.

HUNTER DENNIS, OF WOODLAKE, CALIFORNIA.

PULLEY.

1,305,526.

Specification of Letters Patent.

Patented June 3, 1919.

Application filed July 20, 1918. Serial No. 245,879.

To all whom it may concern:

Be it known that I, HUNTER DENNIS, a citizen of the United States, residing at Woodlake, in the county of Tulare and State 5 of California, have invented certain new and useful Improvements in Pulleys, of which the following is a specification, reference being had to the accompanying drawings.

This invention relates to certain improvements in pulleys, and has relation more particularly to a device of this general character of an expandible type, and it is an object of the invention to provide a novel and improved pulley comprising a sectional rim, 15 and wherein means are provided for effectively connecting adjacent end portions of the rim.

Another object of the invention is to provide a novel and improved pulley of this 20 character including a sectional rim together with fillers insertible between the ends of adjacent sections when said sections are adjusted outwardly relative to the hub of the pulley.

25 The invention consists in the details of construction and in the combination and arrangement of the several parts of my improved pulley whereby certain important advantages are attained and the device is 30 rendered simpler, less expensive and otherwise more convenient and advantageous for use, all as will be hereinafter more fully set forth.

The novel features of the invention will 35 hereinafter be definitely claimed.

In order that my invention may be the better understood, I will now proceed to describe the same with reference to the accompanying drawings, wherein:

40 Figure 1 is a fragmentary view in side elevation with parts in section of a pulley constructed in accordance with an embodiment of my invention and with the segments at the limit of their expansion;

45 Fig. 2 is a fragmentary view in elevation of the inner faces of the end portions of adjacent segments as herein set forth;

50 Fig. 3 is a fragmentary view in side elevation illustrating a modified form of invention;

Fig. 4 is a view in elevation of the inner face portion of the structure as shown in Fig. 3, with certain of the parts in section; and

55 Fig. 5 is a transverse sectional view taken through a filler, as disclosed in Figs. 3 and 4.

As herein disclosed 1 denotes a hub from which radiates the tubular or hollow spokes 2. Telescopically engaged with each of the spokes 2 is an inwardly directed arm 3 carried at substantially a longitudinal center of a section 4 of the rim R. Overlying the adjacent end portions of each set of spokes 2 and arms 3 is an elongated rigid strip of metal 5 having in its opposite end portions 65 longitudinally disposed slots 6. Directed through the slots 6 are the clamping screws 7 in threaded engagement with the spoke 2 and the arm 3 and whereby the arm 3 and the spoke 2 are effectively held in their various relative adjustments and which adjustments are effected when it is desired to expand or contract the rim R.

When the rim R is at the limit of its contraction, the ends of adjacent sections 4 are 75 substantially in contact. One end of each of the sections 4 is provided with an inwardly directed perforated ear 8 and the opposite end portion is provided with a pair of inwardly directed and transversely 80 spaced ears 9. 10 denotes a tie member disposed longitudinally on the requisite curvature and which has one end provided with the forks 11 which are adapted to straddle the ear 8 at one end of a section 4 while the 85 opposite end portion of the member 10 is adapted to snugly fit between the perforate ears 9 at the adjacent end portion of the next succeeding section. The fork 11 is coupled to the ear 8 through the medium of the removable pin 12 and the opposite end portion of the member 10 is coupled to the ears 9 by the removable pin 14 insertible through said ears and the opening 15 in the member 10.

When it is desired to expand the pulley, 95 each of the members 10 is disconnected at one end from one of the sections 4 with which it coacts and the sections 4 are outwardly adjusted by the requisite relative movement of the spokes 2 and arms 3. In 100 the embodiment of my invention as particularly illustrated in Figs. 3, 4, and 5, when the sections 4 are properly positioned, a filler 16 is fitted between the opposed ends of adjacent sections 4. The filler 16 is provided with an inwardly directed arm 17 terminating in a substantially perpendicular extension 18 and which extension 18 is directed substantially circumferentially of the rim R when the filler is in 110 applied position.

The heel portion of the arm 17 is pro-

vided with a pair of transversely spaced ears 19 between which an end portion of the member 10 extends and is coupled thereto by a removable pin in the same manner as has 5 hereinbefore been set forth relative to the coaction of the member 10 directly with two adjacent sections 4. The outer or free end portion of the extension 18 is adapted to fit between a pair of transversely spaced ears 9 10 carried by one of the sections 4 and said free end portion is provided with an opening 20, through which a coupling pin or bolt is disclosed.

It is to be understood that the fillers 16 15 are to be of a length in accordance with the extent of outward adjustments of the sections 4 and that when in applied position, the outer surface or periphery of the fillers will be in continuity with the outer surface 20 or periphery of the sections 4.

In the form of my invention particularly illustrated in Fig. 1, the pulley is expanded, the members or plates 21 are interposed between adjacent sections 4. As particularly 25 illustrated in Fig. 1, the hinged connection between adjacent sections 4 and members or plates 21 is afforded by the rigid straps 22 connected at one end to the ears 8 or 9 of the sections 4, and at their opposite ends 30 with the ears 23 carried by the members or plates 21.

From the foregoing description, it is thought to be obvious that a pulley constructed in accordance with my invention is 35 of an extremely simple and comparatively inexpensive nature and is particularly well adapted for use by reason of the convenience and facility with which it may be assembled, and it will also be obvious that my invention 40 is susceptible of some change and modification without material departure from the principles and spirit thereof, and for this reason I do not wish to be understood as limiting myself to the precise arrangement 45 and formation of the several parts herein shown in carrying out my invention in practice, except as hereinafter claimed.

I claim:—

1. An expandible pulley comprising a sectional rim, means for holding said sections in various radial adjustments, fillers insertible between the ends of adjacent sections of the rim when said sections are radially adjusted outwardly, each of said fillers being provided with an inwardly directed arm terminating in an extension disposed in a direction circumferentially of the rim, means for connecting the free end portion of the extension to the end portion of one of the sections adjacent the filler, and a member connecting the end portion of the second adjacent section and the heel portion of the extension. 50

2. An expandible pulley comprising a sectional rim, means for holding said sections in various radial adjustments, fillers insertible between the ends of adjacent sections of the rim when said sections are radially adjusted outwardly, each of said fillers being provided with an inwardly directed arm terminating in an extension disposed in a direction circumferentially of the rim, means for connecting the free end portion of the extension to the end portion of one of the sections adjacent the filler, and a member connecting the end portion of the second adjacent section and the heel portion of the extension, 60 said member serving to connect the ends of adjacent sections when the filler is removed and the sections are at their 70 limit of contraction. 75

3. A pulley of the class described comprising a sectional rim, means for holding said sections in various radial adjustments, inwardly directed ears carried by the end portions of the sections, and a tie member detachably engageable with the ears of adjacent rim sections. 85

In testimony whereof I hereunto affix my signature in the presence of two witnesses. 90
HUNTER DENNIS.
